UNITED STATES PATENT OFFICE.

ARTHUR L. DAWE, OF MONTREAL, QUEBEC, CANADA.

PAPER-CALENDERING DEVICE.

Application filed August 17, 1927. Serial No. 213,641.

This invention relates to new and useful improvements in paper making machines and particularly to the calendering section thereof.

5 It has been found that owing to the great widths of modern paper making machines and the high speeds at which they operate, that the calendering operation has presented difficulties. In the first place, the calendering rolls which are usually arranged in vertical

10 stacks have become so heavy that the sheet of paper is sometimes crushed and the fibres weakened. Then again, the excessive weight of the long rolls and the heavy 15 weights of same which are required to give a suitable finish or gloss to the paper, has a tendency to cause the rolls to sag or deflect at the centre so that the rolls are not quite parallel.

20 The object of the invention is to provide simple and easily adjusted means which will, when in operation, produce a high gloss or finish on one, or both sides of a sheet of paper, without damaging the texture of 25 same.

Another object is to provide means which will allow a reduction in the number and also the size of the rolls in machines of this class, so that the stack of rolls may be made 30 smaller and any tendency for the rolls to sag may be reduced to a minimum.

A further object is to provide a calendering section which may be easily adapted to the present type of machine without much 35 change in the general design of the supporting structures.

According to my invention I provide a plurality of calender rolls which may be arranged in any desired manner, so that each 40 roll is in contact with the roll, or rolls adjacent thereto, so that paper passing therebetween may be subjected to a squeezing action. The rolls may be heated or cold if so desired. Mounted on the side frames of the 45 calendering section are brackets which pivotally support the finishing rolls, so that they may be quickly and easily brought into and out of contact with the calender rolls. The finishing rolls may be so arranged that they 50 are brought into contact with both sides of the paper passing between them and the calendering rolls. The finishing rolls are rotated at a different circumferential speed from the calendering rolls, so that there will 55 be a slipping or ironing action on the surface of the paper which tends to put a high

gloss on the surface of the paper, such as would be obtained by moving a hot iron thereover. The finishing roll driving shaft is mounted at the centre of the pivot, so that the roll may be quickly withdrawn even while the roll is rotating. Means are provided for adjusting the pressures between the finishing rolls and the calendering rolls, and said means may be arranged to lock the 60 finishing rolls in any desired position.

In the drawings which illustrate my invention:-

Figure 1 is a side elevation of a calendering section of a paper making machine with 70 my improved finishing rolls attached thereto.

Figure 2 is a partial plan of one end of one of the finishing rolls with the driving mechanism shown in detail.

Figure 3 is a side elevation of the part of 75 the machine shown in Figure 2.

Referring more particularly to the drawings, 11 designates the frame of the calendering section of a paper making machine and rotatably mounted in the frame in the usual 80 manner are the rolls 12, which for illustrative purposes are arranged in stack form, that is one above the other with their centres in vertical alignment, but this arrangement may be modified, if so desired. The usual 85 doctors 13 may be provided to clean the roll and prevent the paper from doubling on the roll, or otherwise affecting the smooth working of the machine. The paper moves through the machine in the direction indicated by the arrows and from the upper side 90 of the lower roll is taken to a winding drum, not shown. The rolls may be rotated by any suitable means well known in the art. Secured to the frame are the brackets 14 95 and pivotally mounted in said brackets are the finishing roll supporting levers 15. Rotatably mounted in the ends 16 of the levers are the finishing rolls 17. The other end 18 of the lever is connected to means for moving the levers about their pivots by means of the connecting rods 19, which are made in sections connected together by a turnbuckle 19^a to allow adjustments to be made to the 100 position of the lever.

In the drawings I have shown a manually operated device for adjusting the position of the finishing rolls, but any other type of mechanism may be employed and said mechanism may be hydraulically or electrically 110 operated, if so desired. In the type shown, brackets 20 are secured to the frame of the

machine near the base thereof and rotatably mounted in the said brackets 20 are the spindles 21 which are each provided with a worm 22, which engages with the teeth of a worm wheel 23 which is mounted between bearings 24 and is threaded to engage with the threaded lower end 25 of the connecting rod. Handwheels 26 are secured to the spindles 21 so that on rotation of same, the worms rotate the worm wheels, the threaded bores of which are adapted to move the connecting rods in the vertical direction. The finishing rolls are rotated at a slightly different circumferential speed than the circumferential of the calender roll. The mechanism shown for rotating the finishing rolls comprises motors 27 secured to the frame and adapted to rotate a spindle 28 by means of the chain 29 and chain sprocket wheels 30 and 31. The spindles 28 are rotatably mounted in bearings 29 coincident with the pivoting centres of the levers, and secured to the spindles 28 are the chain sprocket wheels 30 which drive sprocket wheels 31 through the chains 32. The sprocket wheels 31 are secured to the ends of the finishing rolls 17, which are mounted in antifriction bearings 33 mounted in the ends of the levers. This construction allows the finishing rolls to be adjusted without interfering with or affecting the driving mechanism for the finishing rolls.

In operation the paper is passed around the rolls of the calendering machine and moves therethrough in the direction indicated by the arrows. The finishing rolls are then adjusted to contact with and press the paper against the calendering rolls by adjusting the position of the finishing roll supporting levers. In the drawing the mechanisms shown are of the self locking type, being of the double worm type. The driving mechanism for the rolls is set in motion to drive the finishing rolls at a different circumferential speed from that of the calendering rolls, so that there is a certain amount of slip or ironing action on the face of the paper adjacent to the finishing roll, which produces a high gloss or finish on the face of the paper. When the calendering rolls are heated in the usual manner, the rubbing action of the finishing rolls produces a gloss somewhat similar to that produced by moving a hot iron over the surface of the paper. The finishing rolls may be arranged or so mounted on the machine that one or both sides of the paper may be finished with a high gloss.

The device is very simple in construction and it will be readily understood that many modifications may be made in the general construction of the various driving and adjusting mechanisms without departing from the spirit of the invention.

This arrangement also allows less rolls to

be used than in the usual type of machine, as the gloss is not dependent on the weight of the stack rolls acting on the paper. The calendering rolls may be also made of lighter construction and the deflection at the centre of the rolls may be reduced to a minimum. The pressures between the calendering rolls may be also reduced so that the fibres of the paper may not be subjected to strains or pressure which would weaken the paper. The device may be conveniently and easily attached to the types of calendering machines at present in use, whether the rolls are arranged in stack or staggered form. The device herein disclosed is easily adjusted and regulated to give any desired pressure on the paper surface, so that the finish of the paper may be made to suit any required degree of gloss.

Having thus described my invention, what I claim is:

1. In a paper calendering machine having calendering rolls, a finishing roll adapted to run at a different circumferential speed to that of the calendering rolls and in contact with the paper passing therethrough.
2. In a paper calendering machine having a plurality of calendering rolls, a paper finishing device adapted to contact with the paper and press same against the calendering rolls, said finishing device being adapted to slip on the paper surface to produce a high gloss thereon.
3. In a paper calendering machine having a plurality of calendering rolls, a finishing roll, means to rotate the roll at a different circumferential speed to that of the calendering rolls, and means for pressing the finishing roll against the calendering rolls.
4. In a paper making machine having a plurality of calendering rolls rotatably mounted therein, a finishing roll adapted to contact with and press the paper passing through the machine against the calendering rolls, means to adjust the pressure of said finishing roll against the paper, and means to drive the finishing roll at a different circumferential speed to that of the calendering rolls.
5. In a paper calendering machine having a plurality of calendering rolls a finishing roll adapted to contact with and press the paper passing through the machine, pivoted levers supporting the finishing roll, means to pivot the lever to adjust the pressure of the finishing roll against the paper and the calendering roll adjacent thereto, and means adapted to rotate the finishing roll at a different circumferential speed to that of the calendering rolls, said finishing roll being rotatably mounted about the pivot of the levers, so that it is not affected by the movement of the finishing roll.
6. In a calendering machine, a frame, a plurality of calendering rolls mounted there-

- in, between each of which the paper passes through the machine, a finishing roll rotatably mounted on levers pivotally secured to the frame, means for moving the levers to cause the finishing roll to contact with the paper passing through the machine and press the paper against the calendering roll adjacent to the finishing roll, means to regulate said pressure and means driven through the pivot centre of the lever to rotate the finishing roll preferably at a different circumferential speed to that of the calendering rolls.
7. In a calender, a plurality of cooperating rolls adapted to act on a web of paper passing around and between said rolls, means cooperating with one of said rolls adapted to burnish the paper while supported thereon, and means for controlling the pressure of said burnishing means on the paper.
8. In a calender, a series of superimposed
- rolls adapted to act on a web of paper passing therebetween, and means cooperating with one of the last rolls of said series to 25 burnish the paper passing thereover.
9. In a calender, a series of superimposed rolls, guideways for said rolls, a burnisher mounted on said guideways and adapted to cooperate with one of said rolls to act on 30 paper passing therearound, said burnisher being adapted to permit movement of said rolls in said guideways.
10. In a calender, a series of superimposed rolls, spaced guideways for said rolls, a burnisher supported on said guideways and adapted to cooperate with one of said rolls to set on paper passing thereover, said burnisher being adapted to permit upward 40 movement of said rolls in said guideways.

In witness whereof, I have hereunto set my hand.

ARTHUR L. DAWE.
